(57) **CLAIM**

I claim the ornamental design for a pool float, as shown and described.

DESCRIPTION

FIG. 1 is a top plan view of the pool float, showing my novel design;

FIG. 2 is a bottom plan view thereof;

FIG. 3 is a left side view thereof;

FIG. 4 is a right side view thereof;

FIG. 5 is a front elevation view thereof; and,

FIG. 6 is a rear elevation view thereof.
